Primary Examiner — Susan Bennett Hattan*Assistant Examiner* — Janice Hallmark(74) *Attorney, Agent, or Firm* — Haugen Law Firm PLLP(57) **CLAIM**

The ornamental design for an optical phone mount, as shown and described.

DESCRIPTION

FIG. 1 is a back, left, perspective view of the optical phone mount of the present invention;

FIG. 2 is a top, front, plan view of the optical phone mount shown in FIG. 1;

FIG. 3 is a bottom, front, plan view of the optical phone mount shown in FIG. 1;

FIG. 4 is a right, side elevational view of the optical phone mount shown in FIG. 1;

FIG. 5 is a left, side elevational view of the optical phone mount shown in FIG. 1;

FIG. 6 is a back elevational view of the optical phone mount shown in FIG. 1;

FIG. 7 is a front elevational view of the optical phone mount shown in FIG. 1; and,

FIG. 8 is a back, left, perspective view of the optical phone mount of the present invention shown in FIG. 1 and showing the optical phone mount coupled to a rifle component and having a phone camera attached thereto.

The broken lines in the drawings depict environmental subject matter only and form no part of the claimed design.
